CLAIM

The ornamental design for a cup washer as shown and described.

DESCRIPTION

FIG. 1 is a front perspective view of a cup washer showing the new design;

FIG. 2 is rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of the portion designated area "9" in FIG. 1; and,

FIG. 10 is an enlarged detail view of the portion designated area "10" in FIG. 6.

The broken lines shown in the figures are for the purpose of illustrating portions of the cup washer and form no part of the claimed design. The dot-dashed broken lines in the drawings indicate cutoff boundaries for the enlarged detailed portion views and form no part thereof.
